UNITED STATES PATENT OFFICE.

WILLIAM F. KIESEL, JR., OF ALTOONA, PENNSYLVANIA.

CAR-TRUCK.

1,153,117.

Specification of Letters Patent. Patented Sept. 7, 1915.

Application filed July 2, 1914. Serial No. 848,613.

To all whom it may concern:

Be it known that I, WILLIAM F. KIESEL, Jr., a citizen of the United States, and resident of Altoona, county of Blair, State of Pennsylvania, have invented certain new and useful Improvements in Car-Trucks, of which the following is a specification.

My invention relates to car trucks and more particularly to six-wheel trucks.

10 In the present form of equalization devices it has been found necessary to locate the spring beams twice as far from the center axle as from the end axles, in a six-wheel truck, to accomplish proper equalization of 15 the weight on the wheels.

The principal object of my invention is to arrange the equalizer bars on a six-wheel truck so that it will be possible to distribute one-sixth of the load to each wheel and to 20 locate the bolsters and the springs therefor half way between the middle and end journal boxes. The advantage of this arrangement is that the same amount of space is available on both sides of the spring beam 25 for brake head and shoes, permitting the shortest possible wheel base for the truck.

The above and other objects and the novel features of my invention will be apparent from the following description, taken in 30 connection with the drawings, in which—

Figure 1 is a plan view of one-half of a truck embodying my invention; Fig. 2 is a view partly in side elevation and partly in section taken along the line 2—2 of Fig. 1; Fig. 3 is a longitudinal section on the line 3—3 of Fig. 1 looking in the direction of the arrow at the opposite side of the truck; Fig. 4 is a cross section taken on the line 4—4 of Fig. 1; Fig. 5 is a plan view and 35 Fig. 6 a side elevation of the primary equalizer bar; Fig. 7 is a plan view of the secondary equalizer or saddle; Fig. 8 is a longitudinal section taken on the line 8—8 of Fig. 7; Figs. 9 and 10 are respectively a plan 40 view and a longitudinal section on the line 10—10 of Fig. 9 of the spring seat carried by the primary equalizer bar; Figs. 11 and 12 are respectively a side elevation and end elevation of the center pedestal; Figs. 13 45 and 14 are respectively a side elevation and an end elevation of one of the end pedestals; and Fig. 15 is a horizontal cross-section on the line 15—15 of part of the pedestal shown in Fig. 13.

50 Referring to the drawings, 20, 21 and 22 designate the axles of the truck upon which

the wheels 23, 24 and 25 respectively are fixed. Side frame members made up of oppositely facing channel members 27 and 28 are riveted to the top surface and to lateral flanges 29 on the end pedestals P and to the top surface and lateral flanges 30 on the center pedestal P'. The pedestals P and P' are supported on the journal boxes and springs 31 located between cap plates 32 and the top of the journal box form a resilient support, the cap plates 32 being riveted to the opposite inner faces of the webs of the channel plates 27 and 28. The pedestal jaws of the pedestals P and P' fit the journal boxes in the usual manner. The pedestal P' has lugs 33 at the lower end of the jaws thereof and the pedestals P have lugs 34 at the lower end of the inner jaw. The lugs 33 are each connected to a lug 34 by means of 75 the tie rods 35 thereby forming a more rigid structure and bracing the pedestals. At the inner ends of the pedestals P there are bearing or guide surfaces 42 for the purpose of supporting wearing plates for the bolster 80 guides.

Referring to Figs. 5 and 6 the primary equalizer bar 36 comprises a one-piece steel casting, having a hook 37 at one end to engage a plate 38 located on top of the journal box J supported on the center axle 21. The opposite end of the equalizer bar 36 is drilled with a hole 39 and a bolt 40 passes through the hole 39 and through a hole at the lower end of a link 41 which suspends that end of the equalizer bar 36 from the pedestal and thus indirectly from the beam made by the side frame members. It will be seen from Figs. 13, 14 and 15 that each of the pedestals P has an inwardly extending portion 42 95 which is hollow at 43 to receive the upper end of the link 41 and a gib 44 passes through a hole in the upper end of the link 41 and through the holes 45 in the part 42 of the pedestal whereby the end of the equalizer bar 36 is hung from the frame member. Intermediate its ends the equalizer bar 36 is somewhat wider as at 46, where it is bent abruptly and on the inner side of the bent portion 46 there is a seat 47 with a projection 48 to retain in place the spring seat 49 shown in detail in Figs. 9 and 10.

The spring seat 49 is grooved to provide the opposite sides 50 whereby it straddles the equalizer bar 36 and a projection 51 in 110 the groove cooperates with the projection 48 on the bar 36 to keep the seat 49 in place.

The top face of the spring seat 49 has rim flanges 52 against which the last spiral of the spring 53 fits and whereby the latter is held in place.

5 The spring 53 is shown as a double helical spring having a stiffer spring on the outside and it supports one end of the bolster spring saddle or secondary equalizer bar 54 shown in detail in Figs. 7 and 8. The secondary 10 equalizer bar 54 is a one piece steel casting and has at one end a cap 55 with depending rim flanges 56, the cap and flanges fitting the top of the spring 53 and the flanges retaining the same in place. The cap 55 is at 15 the upper end of a right angle extension 57 of the secondary equalizer bar, the said extension being hollow to accommodate the spring on the interior thereof and the bar being inverted U-shape in cross-section at 20 this end so as to straddle the primary equalizer bar. The opposite end 58 of the secondary equalizer bar is bifurcated, the bifurcations thereof having holes 59 to receive the bolt 40, whereby it also is fastened to 25 the link 41 and is thereby suspended from the side frame member of the truck.

Intermediate its ends the secondary equalizer bar 54 has a horizontal portion 60 which is substantially U-shaped in transverse cross- 30 section to straddle the substantially horizontal portion 61 of the primary equalizer bar 36. The top face 62 of the secondary equalizer bar forms a supporting surface for the elliptic spring 63 which carries the bolster 35 64 at one end, it being understood that the bolster is supported at its other end by a similar construction. The primary and secondary equalizer bars are directly beneath and in line with a center line through the 40 members constituting the side frame of the truck and the support of the spring 63 is in the same plane.

The bolsters 64 on opposite sides of the center axle 21 are connected by a suitable 45 stiffened bridge member 65, the ends of which are riveted to each one of the bolsters. The bridge 65 extends across the transverse center line of the truck and has plates riveted thereto, whereby the car body may be 50 pivoted at the center of the truck and supported by the bolsters 64 in the usual manner.

From the foregoing description it will be 55 apparent that the load on the truck is equally distributed to the six wheels thereof by the combination of the primary and secondary equalizer bars, as is shown. Furthermore, the springs which support the bolsters are located half way between the center and 60 end axles leaving more room for the brake heads and shoes. This is a decided advantage in the clasp brake construction herein shown but made the subject-matter of a separate application.

65 While I have shown and described the

construction in detail it is to be understood that the invention is not limited to the exact details as they may be varied to meet different requirements.

Having described my invention what I 70 claim and desire to secure by Letters-Patent is,

1. In a car truck, the combination of a pair of axles, a primary equalizer bar supported by said axles, a secondary equalizer 75 bar supported at one end by one of said axles and at the other end by said primary equalizer bar, and a bolster supporting spring carried by said secondary equalizer bar.

2. In a car truck, the combination of a pair of axles, a primary equalizer bar supported by said axles, a secondary equalizer bar supported at one end by one of said axles and yieldably supported at the opposite end by said primary equalizer bar, said secondary equalizer bar extending on opposite sides of said primary equalizer bar, a bolster, and a spring mounted on the secondary equalizer bar and supporting one end 90 of said bolster.

3. In a car truck, the combination of a pair of axles, a side frame member, means for supporting the side frame member on the axles comprising a pedestal carried by 95 one axle and having an extension, a primary equalizer bar having one end connected to said extension and the other end supported by the other axle, a secondary equalizer bar having one end also supported by said extension and the opposite end supported on the primary equalizer bar, and a bolster supporting spring mounted on said secondary equalizer bar.

4. In a car truck, the combination of a pair of axles, a pedestal mounted on one of said axles and having an extension, an equalizer bar flexibly connected at one end to said extension and having its other end supported from the other axle, a secondary equalizer bar flexibly connected at one end to said extension and having its other end yieldingly supported on the primary equalizer bar, and a bolster supporting spring carried by said secondary equalizer bar midway between the pair of axles.

5. In a six-wheel truck, the combination of a plurality of axles, comprising a center axle and end axles, primary equalizer bars each supported at one end on the center axle, a secondary equalizer bar partly supported on each primary equalizer bar, and a bolster supporting spring mounted on each secondary equalizer bar midway between the center and end axles.

6. In a six-wheel car truck, the combination of a plurality of axles comprising a center axle and end axles on either side of the center axle and means for distributing the load equally to said axles comprising pri- 120 125 130

riary equalizing means between the center axle and each end axle, secondary equalizing means associated with each primary equalizing means, and a bolster supporting spring carried by each secondary equalizing means.

7. In a six-wheel car truck, the combination of axles, a primary equalizer bar supported between two axles and having a substantially horizontal part intermediate its ends, a secondary equalizer bar between said axles and having resilient bearing on said primary equalizer bar and also having a substantially horizontal part intermediate 15 its ends, and a bolster supporting spring mounted on said horizontal part of the secondary equalizer bar above the horizontal part of the primary equalizer bar.

8. In a car truck, the combination of a pair of axles, a bolster, a bolster supporting spring located substantially midway between said axles, and means for supporting

said spring and bolster from said axles comprising a primary equalizer bar and a secondary equalizer bar upon which said spring 25 rests, both said bars being located wholly within the space between said axles.

9. In a six-wheel car truck, the combination of a center axle and two end axles, one on each side of said center axle, two bolster 30 supporting springs, one on each side of said center axle and substantially midway between the latter and each end axle, and a supporting device for said springs comprising pairs of primary and secondary equalizing devices, one pair on each side of the center axle on each side of the truck. 35

In testimony whereof I affix my signature in presence of two witnesses.
